CLAIM

The ornamental design for a taco holder, as shown and described.

DESCRIPTION

FIG. 1 is a diagrammatic perspective view of the taco holder in full lines with tacos shown in broken lines representing environmental association matter being for illustrative purposes only and forming no part of the claimed invention. FIG. 2 is a front elevational view thereof.

FIG. 3 is a rear elevational view thereof.

FIG. 4 is a top plan view of the taco holder; and,

FIG. 5 is a right side elevational view thereof, the left side view being a mirror image of the right side view.
